UNITED STATES PATENT OFFICE.

CAMERON A. KIDD, OF ANSTED, WEST VIRGINIA.

CHIMNEY.

Application filed March 20, 1923. Serial No. 626,407.

To all whom it may concern:

Be it known that I, CAMERON A. KIDD, a citizen of the United States, residing at Ansted, in the county of Fayette and State 5 of West Virginia, have invented a new and useful Chimney, of which the following is a specification.

This invention aims to provide a simple means whereby the products of combustion 10 proceeding from a fire-place communicating with one room may be made effective at the will of an operator, to heat an adjoining room.

It is within the province of the disclosure 15 to improve generally and to enhance the utility of devices of that type to which the invention appertains.

With the above and other objects in view, which will appear as the description proceeds, the invention resides in the combination and arrangement of parts and in the details of construction hereinafter described 20 and claimed, it being understood that, within the scope of what is claimed, changes 25 in the precise embodiment of the invention shown can be made without departing from the spirit of the invention.

In the accompanying drawings:

Figure 1 shows in vertical section, a device 30 constructed in accordance with the invention; Figure 2 is a fragmental vertical section wherein the dampers have been shifted from the position shown in Figure 1.

The numeral 1 marks a floor and the numeral 2 a ceiling, a wall 3 extending between the floor and the ceiling, and defining rooms 4 and 5, on opposite sides of the wall. A heater of any desired sort is provided and may be in the form of a fire place 6 fashioned in the wall 3. The grate of the fire place is marked by the numeral 7. A chimney 8 is provided and communicates with the fire place 6 by way of a passage 9 formed in the wall 3. A flue 10, preferably made of metal is offset horizontally from the chimney 8 and the wall 3 and extends into the room 5. The upper end 11 of the flue 10 enters the chimney 8, and the lower end 12 of the flue passes through a portion of the 45 wall 3 and communicates with the fire place 6. Bearings 14 are mounted in the wall 3 and in the chimney 8. In the bearings 14 a horizontal shaft 15 is journaled for rotation. A damper 16 is secured to the shaft 15 and 50 operates in the flue 10. A damper 17 is secured to the shaft 15 and operates in a

tubular casing 18 located in the chimney 8. The dampers 16 and 17 are disposed at right angles to each other. The ends 19 of the shaft 15 project into the rooms 4 and 5. 60

When the parts are arranged as shown in Figure 1, the damper 17 is in open position, and the damper 16 is in closed position. The products of combustion proceeding from the grate 7, pass through the chimney 8 and not 65 through the flue. Under such circumstances, the room 5 is not heated by radiation from the pipe or flue 10. If desired, the damper 17 may be disposed in closed position, and the damper 16 may be disposed in open position. 70 Then, the passage of the products of combustion through the chimney 8 will be stopped, the products passing through the flue 10, the flue 10 being heated and serving 75 to radiate heat into the room 5. The dampers 16 and 17 may be manipulated either from the room 4 or from the room 5 because the ends of the shaft 15 project into the said rooms.

What is claimed is:—

1. In a device of the class described, separate rooms, a heater so located as to heat one room, a chimney through which the products of combustion pass from the heater, a flue located in the other room and communicating at its ends with the heater and with the chimney, dampers controlling the flue and the chimney, and means for moving one damper to a closed position when the other damper moves to an open position. 80

2. In a device of the class described, a partition forming separate rooms, a fire place located in the partition and so placed as to heat one room, a chimney through which the products of combustion pass 85 from the heater, a flue located in the other room and communicating at its ends with the fire place and with the chimney, a shaft journaled in the partition, in the chimney and in the flue, the ends of the shaft being accessible from either room, and dampers carried by the shaft and operating in the chimney and in the flue, the dampers being so set with respect to each other, that one damper 95 will move toward open position when the other damper moves toward open position. 100

3. In a device of the class described, separate rooms, a heater so located as to heat one room, a chimney through which the products of combustion pass from the heater, a 110 flue located in the other room and communicating at its ends with the heater and with

the chimney, a shaft journaled in the chimney and accessible at its ends from either room, and dampers carried by the shaft, the dampers controlling the chimney and the flue, and being so set that one damper will move toward closed position when the other damper moves toward open position.

In testimony that I claim the foregoing as my own, I have hereto affixed my signature in the presence of two witnesses.

CAMERON A. KIDD.
